UNITED STATES PATENT OFFICE.

ISAAC T. WOODRUFF, OF PORTLAND, OREGON.

AUTOMATIC FEEDER OF MILL-WASTE FUEL FOR DOMESTIC HEATING PLANTS.

Application filed July 26, 1926. Serial No. 125,100.

The object of my device is to provide suitable mechanism adapted for application to furnaces and fire boxes primarily for use as domestic heating units. The device consists primarily of a feeding hopper adapted to being raised and lowered by a lever mechanism to facilitate the refilling of the same, the primary hopper having suitable mechanism disposed in the bottom thereof to shut off the flow of fuel therefrom during the refilling process. A secondary hopper is disposed immediately below the primary hopper and in registering alignment therewith and is secured to the furnace door in such a manner that as the furnace door is opened about its hinged support the secondary hopper is carried out of registry with the primary hopper.

A further object of my invention consists in supporting the primary hopper about link supports in such a manner that the primary hopper may be lowered to facilitate the filling of the same.

My new and improved device is intended primarily for use in the burning of saw mill waste, hog fuel and saw-dust. Fuel of this character is loose and not compact, and is rather voluminous in its general characteristics and requires a primary hopper of substantial magnitude to hold a sufficient quantity to obviate constant attention.

Still further objects of my invention consist in the placing of a flow damper in the primary hopper that is adapted to manual manipulation for the purpose of regulating the flow of the material therepast and into the fire box.

Additional objects of my invention consist in the placing within the fire box of a grate mechanism adapted to permit of the entrance of air through the base of the mass of fuel during the burning of the same to facilitate the combustion of the fuel and to create a live fire at all times.

Additional objects of my invention consist in providing means whereby the fuel to be consumed is deposited centrally of the burning area.

With these and incidental objects in view, the invention consists in certain novel features of construction and combination of parts, the essential elements of which are set forth in the appended claims and a preferred form of embodiment of which is hereinafter shown with reference to the draw-

ings which accompany and form a part of this specification.

In the drawings:—

Fig. 1 is a side elevation of the assembled device, the hopper container is shown in full line position in place ready for use. The same is shown in dotted position as being lowered and adapted for being filled with a new supply of fuel.

Fig. 2 is a top plan view of the mechanism illustrated in Fig. 1.

Fig. 3 is a side elevation partially in section, illustrating the device in place upon a furnace and illustrating the application of the same.

Fig. 4 is a cross section view, taken on line 4—4 of Fig. 3, looking in the direction indicated.

Fig. 5 is a top plan view of a plate to be inserted within the furnace wherein the furnace is designed for hard fuel, as coal or wood, and is designed to prevent the fuel falling through the grates of the ordinary furnace. A rim disposed on the underside of the plate raises the plate free from the grate disposed therebetween.

Fig. 6 is a sectional side elevation of a preferred form of embodiment of my device illustrated in position upon the furnace, adapted for use of hard fuel or for mill waste fuel.

Fig. 7 is a cross section view taken on line 7—7 of Fig. 6, looking in the direction indicated.

Fig. 8 is a front elevation of a furnace having one of my new and improved devices attached thereto and in position for use.

Fig. 9 is a front elevation of the same mechanism illustrated in Fig. 8, with the front door of the furnace open and the lower mechanism of my device in position for the inspection of the inside of the furnace, or for the admittance of fuel into the fire box.

Fig. 10 is a perspective view of a new and improved draft and grate mechanism adapted to facilitate the burning of fuels of the character intended for use in my device. The same shown removed from the fire box.

Like reference characters refer to like parts throughout the several views.

The furnace shell is shown at 1, having an internal fire box 2 disposed within the shell structure. Grates of the usual and ordinary type are shown at 3. If the fire box is of the circular type, or in certain

furnace structures, I have found that best results are obtained when I place within the furnace and disposed immediately above the grate a plate 4, as illustrated in detail in Fig. 5. I place a series of holes 6, through the plate to facilitate the passing of air therethrough during the burning process to facilitate the even passage of air through the fuel during the burning of the fuel. 10 Mill waste fuel, or the so-called hog fuel is generally delivered directly from the mill to the user thereof and carries a large percentage of moisture and is more or less compact and it therefore becomes quite essential to facilitate combustion. This is best accomplished by providing means for the admittance of air through the fuel mass evenly over the fuel area. 15 I have found in the fire box, as illustrated in Fig. 3 and Fig. 4, that a tilting secondary grate 5, will also facilitate combustion and at the same time will maintain a live fire at all times within the fire box. In other types of furnaces I have found that 20 best results are obtained when a grate structure, as illustrated in Fig. 6, Fig. 7, and Fig. 10, is used. An elongated grate 7, is placed centrally of the fire box having a substantially horizontal central section 8, and having disposed at either side of the central section sloping side walls 9, and having an upwardly inclined grate surface 10, disposed at the forward end thereof; a second grate surface 11, is disposed there- 25 beneath, best results being obtained when the air passages 9^a through the side walls, pass through in a substantially horizontal alignment. Disposed immediately below the point of discharge from the feeding 30 hopper and inside the fire door entrance, I place a rearwardly inclined grate surface 12, having a rather coarse series of slots 13. The object of grate surface 12, is two-fold, first, to facilitate combustion and second to 35 distribute and deposit the mass of fuel to be used as nearly centrally of the fire box as possible by gravity means. The primary hopper 14, must be of substantial volume because of the character of fuel to be con- 40 sumed without the constant attention of refilling. A shut off slide 15, is disposed through the base of the hopper to prevent the free flow of fuel therefrom during the filling process or during such time that the 45 secondary feeding hopper may be swung from out of registry with the primary hopper. Where an extremely low fire room ceiling is encountered, or where the fire box door is extremely high, or for other reasons 50 it may be necessary to raise and lower the primary hopper 14, during the filling process, or at other times. This is accomplished by supporting the hopper 14, about the link supports 17, and in hinged relationship 55 therewith. An operating lever 18, is directly

secured to the shaft 19, and as the lever 18 is lowered, the hopper is first raised sufficiently to release the same beyond the central position and as the lever is further lowered, the hopper is then moved forward and 60 is lowered at the same time, as is illustrated in the dotted position, illustrated in Fig. 1. The shaft 19 is journaled in the bracket support 20. A link 21 connects the operating lever 18 with the link 17. The link 17 is 65 journaled about the journal shaft 22, which is supported about the bracket arm 23. A secondary hopper 24 is secured to the furnace door 25, and is adapted to be swung therewith, as the furnace door is opened or 70 closed. As the furnace door is opened or closed, the secondary hopper is swung into and out of registry with the primary feeding hopper. A shaft 26, is disposed across the secondary hopper and an operating 75 lever 27 is secured thereto. The operating lever has a detent disposed thereupon and adapted to register with the quadrant 28. Also secured to the cross shaft 26, is a feeding damper 29 that is adapted to be manipulated and raised or lowered through the 80 action of the operating lever 27. A shield plate 30 is placed directly above the damper 29 and at such an angle as to facilitate the deposit of the fuel thereupon with as little 85 resistance as possible. The raising and lowering of the feeding damper 29 regulates the freedom of flow of the fuel into the fire box. I have found that best results are obtained 90 when the side walls and the front walls of the primary hopper are inclined to a common point and would meet at a common point if extended. Combustion is further 95 regulated by the placing of an air inlet pipe 31 in the fire box. 100

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follows: 105

What I claim is:—

1. In combination in a new and improved automatic feeder of mill waste fuel for domestic heating plants of a primary hopper, means for raising and lowering said primary hopper, a slidably cut off disposed across the base of the primary hopper, a secondary hopper disposed in registering alignment with the primary hopper and adapted to being swung into and out of registry with the primary hopper, a feeding damper disposed in the secondary hopper and an operating lever and a quadrant adapted to manual manipulation to regulate the feeding damper. 115
2. In combination in a new and improved 120

automatic feeder of mill waste fuel for domestic heating plants, of a primary hopper having sloping front and side walls, lever means for raising and lowering said primary hopper, a slideable cut off disposed across the base of said hopper, a secondary hopper secured to the furnace door of the furnace, in registering alignment with the primary hopper, and adapted to being swung into and out of registry with the primary hopper, a feeding damper adapted to manual manipulation disposed within the secondary hopper and means adapted to maintain the feeding damper in placed position.

15 3. In combination in a new and improved automatic feeder of mill waste fuel for domestic heating plants of primary and secondary hoppers in registering alignment with each other, independent means for 20 swinging either of the hoppers out of alignment and registry with the other, damper regulating means disposed in each hopper, grates adapted to deposit the fuel as fed substantially centrally of the fire box of the furnace and a secondary grate rearwardly inclined disposed above the primary grates of 25 the furnace.

4. In combination in a new and improved automatic feeder of mill waste fuel for domestic heating plants of primary and secondary feeding hoppers in registering alignment with each other, independent means for moving either of the hoppers out of registry with the other, means disposed in each hopper adapted to restrict the flow of fuel therefrom, grate means disposed at the point of discharge from the secondary hopper adapted to deposit the fuel substantially centrally of the fire box and a grate having a substantially horizontal central section having sloping side walls and horizontal draft slots disposed central of the fire box.

5. In combination in a new and improved automatic feeder of mill waste fuel for domestic heating plants of primary and secondary feeding hoppers in registered alignment with each other, independent means for moving either of the hoppers out of registry with the other, a damper regulator disposed in each hopper and an elevated grate section disposed within the fire box at the point of discharge of the fuel from the secondary hopper into the fire box.

ISAAC T. WOODRUFF.
